Primary Examiner — Cynthia Ramirez

Assistant Examiner — Tamara L Hahn

(57) **CLAIM**

The ornamental design for an oral care implement, as shown and described.

DESCRIPTION

FIG. 1 is a front perspective view of an oral care implement according to the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view thereof.

The broken lines illustrate portions of the oral care implement that form no part of the claimed design.

1 Claim, 5 Drawing Sheets
